UNITED STATES PATENT OFFICE.

HENRY SCHOEFFLER, OF BROOKLYN, NEW YORK, ASSIGNOR TO JOHN TIMMES, OF SAME PLACE.

DESIGN FOR GATE.

Specification forming part of Design No. **11,444**, dated September 30, 1879; application filed August 20, 1879.
[Term of patent 7 years.]

To all whom it may concern:

Be it known that I, HENRY SCHOEFFLER, of Brooklyn, in the county of Kings and State of New York, have originated a new Design for Gates, of which the following is a full, clear, and exact description, reference being had to the accompanying photographic illustration, making part of this specification.

The accompanying photographic view shows a gate of my design, which I will now proceed to describe.

The letter A designates two posts with top and bottom ornaments, the top ornaments consisting of a capital, b, moldings c, and a peak, d, while the bottom ornaments consist of a base, e, prism f, and knob g.

The letter B designates a base rail, and C a top rail, connecting the posts A, the said rail having re-entering curved ends, as shown. The base-rail B is straight, and carries a row of pendent knobs, h, while the top rail, C, is arched and perforated near its ends, as at i.

The letter D designates a vase with flowers, and E foliage, both surmounting the top rail, C, the foliage being on opposite sides of the vase.

Intermediate of the two rails B C are scrolls G H, which are represented as emanating, together with a bunch of leaves, I, from an ornamented band having a row of beads. The

scrolls G extend in a lower direction, and from the ends thereof, where they vanish in rosettes k, depend beads l, these beads being represented as sustained by strings. The scrolls H extend in an upper direction, and are joined near their ends by a crown, m.

By these feature I obtain a design of handsome and distinguishing character.

What I claim as new, and desire to secure by Letters Patent, is—

1. The design for a gate, consisting, essentially, of the intermediate scrolls G H, emanating from a bunch of leaves, I, and a crown, m, arranged above the leaves, all as herein described, and shown in the accompanying facsimile.

2. The design for a gate, consisting, essentially, of the intermediate scrolls G H, emanating from a bunch of leaves, I, the crown m, arranged above the leaves, and the side rosettes, k k, having pendent beads l l, all as herein described, and shown in the accompanying facsimile.

In testimony that I claim the foregoing I have hereunto set my hand and seal this 4th day of August, 1879.

HENRY SCHOEFFLER. [L. S.]
